KNIFE

George N. Kirangelos, New York, N. Y.

Application June 3, 1935, Serial No. 24,737

3 Claims. (Cl. 30—9)

This invention relates to a knife designed primarily for cutting fur skins, but it is to be understood that it is for use in any connection where it is found to be applicable.

5 The essential objects of the invention are to provide, in a manner as hereinafter set forth, a knife for the purpose referred to of a construction to permit of a blade being readily removed and a new blade substituted when occasion requires; to provide for the folding of the blade in an encased manner when the knife is not in use thereby preventing injury from the cutting edge of the blade, more especially from the point of the blade if the knife is dropped; to latch the 10 blade in extended position when using the knife to prevent the folding of the latter; to prevent any injury from the point and cutting edge of the blade when the knife is closed; to overcome the necessity of employing a separate enclosing 15 casing for the knife when the latter is carried upon the person; to protect the bearing finger of the operator when using the knife; to protect the cutting edge of the blade of the knife when the latter is not in use; to provide the handle 20 of the knife as a protector for the blade when the latter is folded; and to so form the knife handle as to permit it to be provided with a scale as a convenience to the operator.

Further objects of the invention are to provide, 25 in a manner as hereinafter set forth, a knife for the purpose referred to which is simple in its construction and arrangement, strong, durable, compact, thoroughly efficient for the purpose intended thereby, readily assembled and comparatively inexpensive to manufacture.

To the above ends essentially and to others which may hereinafter appear, the invention consists of such parts which will be described and as illustrated in the accompanying drawing, 30 wherein is shown an embodiment of the invention, but it is to be understood that changes, variations and modifications may be resorted to which fall within the scope of the invention as claimed.

45 In the drawing:

Figure 1 is a side elevation of the knife when open and illustrating in full and dotted lines the finger guard in operative and inoperative positions respectively.

50 Figure 2 is a side elevation of the knife when open with a section of the handle element and a section of the blade coupling element removed and further illustrating in dotted lines the position of the blade and the blade coupling element 55 when the knife is closed.

Figure 3 is a bottom plan view of the knife in open position,

Figure 4 is a section on line 4—4, Figure 2, Figure 5 is a section on line 5—5, Figure 1,

Figure 6 is a side elevation of the blade, and 5 Figure 7 is an elevation of a modified form of blade capable of being reversed.

The knife includes a combined case, guard and handle element 7, a combined blade carrier and coupling element 8, a blade 8^a, a combined 10 finger guard and blade locking element 9, a latching device 10 for retaining the knife in open position, and a pivot element 11 common to elements 7 and 8.

The element 7 includes a pair of outer sections 15 12, 13 and an intermediate section 14 which 20 co-acts with the said other sections to form a case with a closed top, partly open inner and outer ends and a completely open bottom. The sections 12, 13 are of like contour and each has its 25 forward end formed with a lower semi-circular edge portion 15 and an upper edge portion 16 which is inset with respect to edge portion 15. The edge portion 16 is disposed at an outward 30 inclination from its lower to its upper end. The inner end of the top of edge portion 15 merges into the lower end of edge portion 16. The sections 12, 13 have rounded rear end edges 17, curved top and bottom edges 18, 19 extending 35 respectively from the upper and lower ends of edge 17. The forward portion of edge 18 is upon an outwardly directed curve and has its forward end merging into the outer end of edge portion 16. The edge 19 is straight and inclines downwardly from the bottom of edge 17 and 40 terminates in the end of the bottom of the edge portion 15. The edge portions 16 are parallel 45 and constitute an abutment for a purpose to be referred to. The sections 12, 13 have aligning openings 20 arranged below edge portions 16. The section 14 is in the form of a narrow strap 50 having its outer side edge conforming in contour to the top edges 18 and the upper portion of the edges 17 of sections 12, 13. The section 14 is narrow and of angle contour to provide an elongated upper, horizontal leg 21 and an 55 upstanding leg 22 depending from the outer end of leg 21. The forward end of leg 21 is of the same contour as the edge portions 16. The section 14 is flush with edge portions 16 and edges 17 and 18. The bottom edge of leg 21 is cut out to provide a shoulder 23 intermediate its ends.

The sections 12, 13 are formed with parallel bayonet shaped slots 24 arranged at and depending below the bottom edge of leg 21. The 55

sections 12, 13 and 14 are suitably secured together. The outer faces of the sections 12, 13 bordering the edges 19 are provided with graduated scales 25, only one shown.

5 The combined blade carrier and coupling element 8 comprises a pair of resilient side cheeks 25, 26 extending between the inner ends of sections 12, 13 of element 7. Each cheek is formed of a substantially triangular shaped part 27 and 10 an offset rearwardly extending, downwardly inclined circular extension 28. The upper portions of the rear ends of the cheeks 25, 26, above the extensions 28, are provided with edge portions 29 which extend at an inclination from their lower 15 to their upper ends in a direction toward the forward ends of the cheeks. The extensions 28 are formed with axially arranged openings 30. The cheek 25, in proximity to its bottom end edge forwardly of its extension 28, has anchored thereto 20 forward and rear spaced blade holding pins 31, 31^a respectively which extend towards cheek 26 and are formed with reduced parts 32 whereby the pins are shouldered, as at 33. The axis of pin 31^a is arranged above the axis of pin 31. The cheek 25, 26, in proximity to its bottom edge forwardly of 25 its extension 28, is provided with forward and rear spaced openings 34, 34^a respectively, for receiving the reduced parts 32 of the pins. The axis of opening 34^a is arranged above the axis of opening 34. When the reduced parts 32 are extended 30 into the openings 34, 34^a the shoulders 33 abut against the inner face of cheek 26. The cheeks are arranged in parallel spaced relation for the reception therebetween of the upper portion of the 35 blade 8^a and for this purpose there is secured to the inner face of the cheek 25 a disc 35 which has its edge flush with the extensions 28. The disc 35 is formed with an axial opening 36 which is to align with the openings 30 in extensions 28. 40 The disc 35, at its edge, is formed with spaced cutouts, as at 37, 38, to provide respectively a combined clearance and abutment and a ratchet tooth for purposes to be referred to. The forward side edges of cheeks 25, 26 have aligning cutouts 45 39 for a purpose to be set forth. The cutouts 39 form upper and lower shoulders and inset forward edge portions connecting the upper shoulders to the lower shoulders.

The blade element 8^a is of substantial frusto 50 triangular form and consists of a body part 40 having a cutting edge 41, a front edge formed of a pair of rearwardly inclined superposed edge portions 42, 43 disposed in parallel planes and with the edge portion 43 arranged below and forwardly 55 of edge portion 42, a straight upper edge 44 of materially less length than its cutting edge and a rear edge formed of a lower straight edge portion 45 and an upper edge portion 46 extending forwardly at an inclination from the upper end of of 60 edge portion 45 to the rear end of edge 44. The edge portions 42, 43 are at a greater inclination than that of edge portion 46. The latter is of materially greater length than edge portion 45. The body part 40 is provided above its longitudinal 65 median with a forward and a rear opening 47, 48 respectively and with opening 48 having its axis arranged above the axis of opening 47.

70 It will be noted that the extensions 28, in the open condition of the knife have an edge portion curving away from the bottom edge of the handle and extending beyond the open end of the latter and that the cutting edge 41 of the blade element 8^a inclines away from said edge and is offset inwardly of the latter whereby in cutting an edge 75 of a skin, for instance on a table, the knife ele-

ment may be positioned over the edge of the skin and rocked downwardly the extensions being used as a fulcrum bearing upon the table.

The finger guard element 9, which also constitutes a lock for blade 8^a and coacts with the outer ends of the cheeks 25, 26, consists of a channel shaped body 49 having integral with the upper end of one side thereof an apertured arm 50 which is pivotally connected, as at 51, to and is arranged against the outer side of cheek 25. The element 9, in connection with the pins 31, 31^a, releasably lock the blade 8^a to the element 8. The blade is inserted between the cheeks to a position whereby the non-reduced parts of the pins 31, 31^a will be arranged in the openings 47, 48. 15 The cheek 26 is then moved towards cheek 25 to provide for the reduced parts 32 to extend into the openings 34, 34^a. The element 9 is then shifted from its dotted line position (Figure 1) to its full line position (Figure 1) whereby the 20 blade will be removably locked to the cheeks in position to be used. When the body 49 of element 9 is in its full line position (Figure 1) it will seat in the cutouts 39 and against edge portion 42 of the blade, as well as straddle and be 25 flush with the outer end edges of the cheeks and the edge portion 43 of the blade. When the knife is used one of the operator's fingers bears on the body 49 of element 9 and such body prevents the finger from being injured by the outer end edges 30 of the cheeks and blade. When the latter is detachably secured to the cheeks it has a part of its rear edge abutting the edge of the cutout 31. The edge of the latter is of a contour similar to the edge portions 45, 46 of the blade. 35

Since the cheeks 25 and 26, as previously mentioned, are resilient they may be flexed away from each other to break the coaction of the pins 31, 31^a with the openings 34, 34^a and to facilitate inserting and removing the blade element 8^a. By 40 swinging one cheek relative to the other access may be had to the interior of the blade carrier for convenient manipulation of the blade element in inserting or removing the same. As will be apparent the cheeks 25 and 26 are locked against 45 such relative movement by coaction of the element 9 with the cut outs 39.

Positioned against the outer faces of the sections 12, 13 of the element 7 are axially apertured discs 52. The apertures of the discs 52 align 50 with the openings 20, 30, 36. Countersunk in the apertures of the discs 52 and extending through the openings 20, 30, 36 is the pivot element 11. The latter and discs 52 clamp elements 7 and 8 together to prevent one freely moving relative to 55 the other, but the clamping action is such as to permit the knife to be opened and closed when occasion requires.

The latching device 10 coacts with the ratchet tooth formed by cutout 38 for the purpose of 60 maintaining the knife in open position, such as shown in Figures 1, 2, and 3. The device 10 is spring controlled and includes a latching member 53 slidably mounted on a lug 54 on the inner face of section 12, a pull member 55 for and pivotally 65 connected to member 53, as at 56, an arm 57 carried by member 55 and extending through the slots 24 and finger pieces 58 on the ends of arm 57 to facilitate the shifting of device 10 to and from latching position. The controlling spring 70 of the device 10 is indicated at 59.

The pull member 55, when latching member 53 in engagement with the ratchet tooth formed by cutout 38, is to abut the shoulder 23 whereby the latching device 10 will be maintained in a 75

position to prevent the shifting of the combined blade carrier and coupling element 8 on pivot element 11. When the latching device 10 is released, the knife can be closed in a manner whereby element 8 and blade 8^a will be arranged in the dotted line position shown in Figure 2, that is, the portion of the blade extended from element 8 and a part of the latter will be encased by element 7.

The edge portions 16 and 29 coact for limiting 10 the opening of the knife and to cause the elements 7 and 8 to extend in lateral relation with respect to each other.

The bayonet slots 24 and arm 57 coact under the influence of the controlling spring 59, when 15 the device 10 is moved to locking position to form snap-action devices for holding the element 10 in latching position.

The modified form of blade element shown in Figure 6 is designated 60 and is in the form of a 20 symmetrical trapezoid. The element 60 is formed with a pair of spaced openings 61 which are parallel to its cutting edge 62. The element 60 is reversible. The forward portion of disc 35 will be cut away in a suitable manner to provide a clearance which would be common to the front and rear edges of the element 60 when the latter is used in normal or reversed positions.

What I claim is:

1. A knife for use in cutting material upon a 30 flat support and comprising, a hollow handle having a rib-like back member extending along one edge and open at its opposite edge and one end respectively, a blade holder adapted to be swung into and out of said handle to open and close the 35 knife and comprising, a pair of laterally spaced cheek plates having extending therefrom substantially semi-circular ears pivotally secured, in the open end of the handle, each of said ears having an edge portion extending, in the open 40 condition of the knife, beyond the open end of the handle whereby said holder may be rocked upon the support with a rolling motion by means of said handle and pressure exerted downwardly thereon, said ears bearing against said back member whereby the pivot of the holder is relieved of 45 such pressure and shearing of said pivot thereby

obviated, and a knife blade removably secured between said cheek plates, and having a cutting edge inclining, in the open condition of the knife, away from the open edge of the handle and offset inwardly of said edge whereby said blade may be 5 positioned to overly an edge of the material for downward rocking movement of the blade by said movement of the blade holder.

2. In a knife, a hollow handle open at one edge and one end, respectively, a knife blade having 10 apertures therein, a blade holder pivotally mounted in said end of the handle and comprising opposed cheek plates laterally spaced to receive said blade therebetween and provided with coacting devices cooperating with said apertures to secure 15 the blade between said plates, said plates being resilient for separative flexing action to break the coaction between said devices and swingable independently of each other for access to said blade, and a combined locking element and finger- 20 guard for securing said plates against such flexing action and for applying pressure against said holder, said element being pivotally mounted on one plate to fold over the edges of said plates and in its folded position being countersunk in said 25 edges whereby said plates are held against independent swinging movement.

3. In a knife, a hollow handle having a rib-like back member extending along one edge thereof and open at its opposite edge and one end respectively, a blade, a blade holder adapted to swing into and out of said handle and comprising, laterally spaced cheek plates having extending therefrom substantially semi-circular ears pivotally secured in the open end of the handle 35 and bearing at their edges against said back member, one of said ears being provided with a notch for location, in the outwardly swung position of the holder, contiguous said back member, and means to lock the holder in outwardly 40 swung position and comprising a locking bolt slideable on said member into said notch, a manipulative element for sliding said bolt, and snap action devices for latching said element to said handle in the locking position of said bolt.

GEORGE N. KIRANGELOS. 45
